DAVID OSBURN. INVENTOR

By *Victor J. Evans*

ATTORNEY

UNITED STATES PATENT OFFICE.

DAVID OSBURN, OF GRINDSTONE, PENNSYLVANIA.

SWITCH THROW.

Application filed February 27, 1925. Serial No. 12,063.

To all whom it may concern:

Be it known that I, DAVID OSBURN, a citizen of the United States, residing at Grindstone, in the county of Fayette and State of Pennsylvania, have invented new and useful Improvements in Switch Throws, of which the following is a specification.

This invention relates to switch operating means, and more particularly to a switch throw intended for use in mines.

One of the main objects of the invention is to provide a switch throw of simple construction and operation which may be used as a "spring" switch or a "throw" switch or a combination of both. A further object is to provide a switch throw so constructed as to eliminate breakage of parts as a result of strains to which they are subjected in use. Further objects will appear from the detail description.

In the drawings:

Figure 1 is a top plan view of the switch throw;

Figure 2 is a side view;

Figure 3 is a section taken substantially on line 3—3 of Fig. 2;

Figure 4 is a section taken substantially on line 4—4 of Fig. 5;

Figure 5 is a side view of the supporting structure;

Figure 6 is a diagrammatic view illustrating the use of the switch throw in connection with a siding;

Figure 7 is a diagrammatic view illustrating the use of a switch throw in connection with a spur track.

The present invention is intended more particularly as an improvement over the switch throw disclosed in my patent for switch-throwing device, No. 1,024,279 issued April 23, 1912. The device of my patent is held in operative position by a tension spring which has been found to be unsatisfactory in some respects in that the spring is liable to breakage under continued use for a long period of time. A further objection to the device of my patent is that this device is used as a spring switch only and cannot be adjusted to be used as a combination spring and throw switch or as a throw switch. The invention of this application avoids these objections and provides

a device which is thoroughly practical and highly efficient in its operation. In the improved form of my device I provide a supporting structure which includes two frames 1 of approximately inverted U-shape which are provided, at their lower ends, with offset legs 2 and with securing feet 3 disposed in angular relation to the legs, these feet being adapted for reception of lag screws by means of which the frame is secured to adjacent ties of a railway, as indicated. Two semicircular members 4 are secured between frames 1 by riveting or in any other suitable or preferred manner, these members being offset outwardly so as to be spaced apart from each other at their central portions thus providing a slot 5 for reception of an operating lever 6 which is pivotally secured between members 4 by means of a bolt 7 which is positioned between the ends of lever 6. A rod 8 of a switch bridle is secured to a clevis 9 which is pivotally secured by a bolt 10 to the lower end of lever 6. The upper end of lever 6 is pivotally secured by a bolt 11 to the lower end of a control lever 12 which projects upwardly between the upper approximately semi-circular portions of frames 1, these frames being held in spaced relation by the end portions of members 4 and cooperating with these members to form a circular frame the upper portion of which guides the control lever and the lower portion of which guides the operating lever as described. To hold the control lever 12 in operative position I provide stop pins 13 which are inserted through any one, selectively, of a plurality of openings 14 provided through the upper portions of frames 1, the corresponding openings of the respective frames being disposed in alignment. An angle bracket 15 is pivotally secured to lever 12 above frames 1 by a bolt 16 and a similar bracket 17 is similarly secured to lever 16 adjacent the lower end thereof. A headed rod 18 extends through the outwardly projecting arm of bracket 15 and through two plates or clips 19, this rod being held against withdrawal through the lower clip 19 by a nut 20 threaded onto the rod. A similar rod 18a extends through the outer arm of bracket 17 and through the clips 19, a nut 20a being threaded on the

upper end of this rod. An expansion coil spring 21 is mounted about the rods and is confined between clips 19. This spring acts by expansive force to urge the levers 6 and 12 toward each other about pin or bolt 11, these levers constituting, in effect, a toggle which is normally held in broken position with the pivot 11 positioned to one side of a vertical plane coincident with the axis of pivot pin or bolt 7. In Figure 2 levers 6 and 12 are held in the positions illustrated by the combined action of spring 21 and the stop pins 13 which are positioned in the uppermost pair of openings 14. In this position, when the switch points to which the rod 8 is connected are opened against the action of the spring 21, lever 6 is rocked about its pivot 7 in the direction indicated such a distance as to bring pivot 11 beyond the center of the supporting structure, at which time spring 21 acts to complete the throw of the switch thus holding the switch points in open position, the levers 6 and 12 being positioned oppositely to the positions illustrated in Figure 2. By placing the pins in the third pair of openings 14 from the center, the levers 6 and 12 are disposed at such an angle to each other that the pivot point 11 is beyond the center of the frame such a distance that, when the switch point is opened by the flange of a car wheel, the movement of rod 8 will not be sufficient to move the pivot point 11 beyond center in the opposite direction. In this case, after a car has passed through the switch, the switch points will be returned to their original positions by the action of spring 21 and parts associated therewith. By placing one of the pins 13 in the uppermost pair of one series of openings and the other pin 13 in the third pair from the top of the other series of openings, the device may be so set that it will act as a spring switch in one direction and a throw switch in the opposite direction.

In Figures 6 and 7 I have indicated diagrammatically the various uses of my switch throw. In Figure 6 the device indicated at *a* is set as a spring switch, the device indicated at *b* being set as a spring switch in one direction and a throw switch in the other direction. In Figure 6, the device is so set that the switch is closed so as to direct a car from the main track M onto a siding S which leads onto the main track at *s*, this main track leading to a dump D. The device at *b* is set so as to act as a spring switch for cars passing off of the siding S onto the main track and as a throw switch for cars traveling down portion *m* of the main track to the dump. With the two devices set in this manner, cars traveling toward the siding S on the main track will be diverted onto the siding S which, in practice, would lead into galleries or rooms being worked

and, after being loaded, these cars continue to travel upon the siding onto the main track at *s* along which they travel to the dump. After being dumped the cars travel back along the main track to the point *s* at which point they are diverted onto the siding to be again loaded. In the event that it is desired to move a trip of cars from the siding onto the main track in a direction away from the dump, the cars will travel from the siding onto the main track at *a*, the switch at this end of the siding remaining closed. In the event that it is desired to take a trip of cars to the dump on the main track without going onto the siding, the device at *a* is operated manually so as to open the switch permitting the trip to enter portion *m* of the main track, after which the device at *a* is returned to its original setting so as to close the switch. When the trip reaches point *s* on the main track the switch point is operated by the flange of the car wheel and the switch is opened, and held open by the device *b*, which acts as a throw switch in this direction. Upon return of the trip from the dump D, it continues to travel upon the main track as the switch at *s* is open, traveling along portion *m* of the main track. As the trip reaches the switch at *a*, the switch point is displaced by the flange of the car wheel but is immediately returned to closed position since the throw at this point is set as a spring switch. This keeps the switch at *a* closed so that a second trip traveling upon main track M toward the dump will be directed onto the siding S upon which it can travel onto the main track and along the main track to the dump. As this second trip enters the siding at point *s*, the switch point in the main track will be displaced by the flange of the car wheel but will be immediately returned to its position adjacent the main track rail by the action of the device *b* which is set to act as a spring switch in this direction. This keeps the switch at *s* open so that upon return of this second trip it will travel through the switch at *s* along the main track to and through the switch at *a*. If, however, it is desired to direct this second trip onto the siding S the device at *b* is operated manually to close the switch at *s* thus directing the second trip from the main track onto the siding. In Figure 7 the device is shown as used in connection with a main track M and a spur track ST, the main track leading to the dump D. The device *c*, in this instance, is set to act as a throw switch in both directions. With the switch points closed as indicated, a trip traveling along the main track to the dump will displace the switch points and the throw of the switch points will be completed and the switch will be held open by the device at

c, thus permitting the trip to return from the dump along the main track without entering the spur track. A trip traveling along the spur track toward the dump will 5 displace the switch points and the device at *c* will complete the throw of these points closing the switch so that, upon return of this second trip it will be directed onto the spur track. The device used in this manner is entirely automatic and eliminates any 10 necessity of an operator setting the device manually.

What I claim is:—

1. In a switch throwing device, a supporting structure, an operating lever pivotally mounted between its ends on said structure, a switch bridle rod connected to one end of said lever, a control lever pivotally connected to the other end of the operating lever, means urging the levers toward each other about their pivotal connection while permitting movement of the levers away from each other when pressure in the proper direction is applied to either 20 lever, and adjustable means for limiting movement of the control lever in either direction about its pivotal connection with the operating lever.

2. In a switch throwing device, a supporting structure, an operating lever pivotally mounted between its ends on said structure, a switch bridle rod connected to one end of said lever, a control lever pivotally connected at one end to the other end of the operating lever, resilient means acting under compression to urge the levers toward each other about their pivotal connection, and adjustable means for limiting movement of the control lever in either 40 direction about its pivotal connection with the operating lever.

3. In a switch throwing device, a supporting structure including two members disposed in spaced parallel relation and forming a guiding frame, an operating lever pivotally mounted between its ends on the supporting structure, a switch bridle rod pivotally secured to the end of the operating lever remote from said guiding frame, a control lever pivotally connected to the other end of the operating lever and extending loosely through the guiding frame, resilient means acting to urge the levers toward each other about their pivotal connection, and adjustable means for limiting movement of the control lever in either 50 direction.

4. In a switch throwing device, a supporting structure, an operating lever pivotally mounted between its ends on said structure, a switch bridle rod pivotally secured to one end of the operating lever, a control lever pivotally connected at one end to the other end of the operating lever, resilient means urging the levers toward 60

each other about their pivotal connection, and adjustable means for limiting movement of the control lever in either direction.

5. In a switch throwing device, a supporting structure, an operating lever pivotally mounted between its ends on said structure, a switch bridle rod pivotally secured to one end of the operating lever, a control lever pivotally connected at one end to the other end of the operating lever, resilient means urging the levers toward each other about their pivotal connection, and adjustable means for limiting movement of the control lever in either direction, 70 the means for limiting movement of the control lever in one direction being adjustable independently of the means for limiting movement of the control lever in the other direction whereby said limiting means may be adjusted to permit greater movement of said control lever in one direction than in the other direction.

6. In a switch throwing device, a supporting structure including a guiding frame, an operating lever pivotally mounted between its ends on the structures remote from the guiding frame, a switch bridle rod pivotally secured to the end of the operating lever remote from said guiding frame, a control lever pivotally connected at one end to the other end of the guiding frame and extending loosely through said frame, resilient means acting under compression to urge the levers toward each other about their pivotal connection, and adjustable means for limiting movement of the control lever in either 90 direction.

7. In a switch throwing device, a supporting structure including a guiding frame, an operating lever pivotally mounted on the supporting structure remote from said frame, a switch bridle rod pivotally secured to the end of the lever remote from the guiding frame, a control lever pivotally connected at one end to the other end of the operating lever and extending loosely through the guiding frame, said frame being provided with series of pairs of aligned openings, stop pins inserted through selected pairs of the openings and acting to limit movement of the control lever in either direction, and resilient means for urging the levers toward each other about their pivotal connection.

8. In a switch throwing device, a supporting structure, an operating lever pivotally mounted between its ends on said structure, a switch bridle rod pivotally secured to the end of the lever remote from the structure, a control lever pivotally secured at one end to the other end of the other lever, the supporting structure including a guide frame loosely receiving the 110 120 125 130

control lever, means for limiting movement of the control lever in the guide frame, plates, rods connected to the respective levers and slideable through said plates, an expansion spring mounted about said rods and confined between the plates and acting under compression to urge the levers to-

ward each other about their pivotal connection, and means for preventing withdrawal of the rods through the plates, said means being adjustable to vary the compression of the spring. ¹⁰

In testimony whereof I affix my signature.
DAVID OSBURN,
